UNITED STATES PATENT OFFICE.

JOHN McGREER, OF CHICAGO, ILLINOIS.

AUTOMATIC ADVERTISING DEVICE.

SPECIFICATION forming part of Letters Patent No. 319,597, dated June 9, 1885.

Application filed May 3, 1884. (No model.)

To all whom it may concern:

Be it known that I, JOHN McGREER, a citizen of the United States, residing at Chicago, in the county of Cook and State of Illinois, have 5 invented certain new and useful Improvements in Automatic Advertising Devices, of which I do declare the following to be a full, clear, and exact description, reference being had to the accompanying drawings, forming part of 10 this specification.

My present invention has for its object to provide an improved construction of advertising device, whereby a series of pictures or other attractive cards may be successively and 15 automatically displayed in connection with advertisements to which the attention of the public will thus be directed. This object I have accomplished by the mechanism hereinafter described, and illustrated in the accompanying 20 drawings, the invention consisting in certain details of construction, to be particularly defined in the claims at the end of the specification.

Figure 1 is a view in front elevation of my improved advertising device, parts being broken away for the purpose of better illustration. Fig. 2 is a side view with parts broken away. Fig. 3 is an enlarged detail view, in longitudinal section, of the display-drum and connected 25 parts. Fig. 4 is a sectional view on line $x-x$ of Fig. 3. Fig. 5 is a transverse sectional view of the drum, a portion of one end being broken away to show subjacent parts. Fig. 6 is a detail view, in transverse section, of one of the 30 cards and its sustaining-rod.

Like letters of reference denote corresponding parts in the several views of the drawings.

A designates the main casing, the front A' of which is cut away, as shown, to form an 40 opening through which the cards may be seen. Within this casing, at a point about opposite the center of the front opening, is placed the display-drum B, that is sustained by means of the shaft C, having its ends journaled, respectively, in one side of the casing and in the journal-block c, attached to opposite side. The drum B consists, preferably, of a paper cylinder having its exterior suitably ornamented, and having the heads b, to which are attached 45 the plates D D', that project beyond the periphery of the drum, and are provided with

the perforations d, to receive the rods E, that enter the pockets formed by the strips f, attached to the cards F, and thus serve to hold the cards securely upon the drum. Perforations d' are also formed in the end of the plate D, to receive staples d', that fit over the bent ends of the rods and retain them in place. From this construction it will be seen that in order to secure the cards upon the drum it is 55 only necessary to withdraw the staples d' and slip backward the rods until out of the plate D, when their free ends may be thrown outward, and the cards may be placed thereon. 60

Each of the cards F is provided, preferably, 65 upon one side with a picture to attract the eye, and upon the opposite side with an advertisement, so that as the drum revolves the card will successively display the picture and the advertisement.

Upon the side of the plate D is pivotally held the pawl g, that is pressed downward by the spring g', and engages with the ratchet-wheel G, attached to the end of the cord-pulley H, that is keyed to the shaft C. 70

To the opposite end of the pulley H is connected the ratchet-wheel H', with which engages the pawl I, that is carried by the main cog-wheel I', loosely journaled on the shaft C, and held in place by means of the washer i. 80 A pinion, K, the shaft of which is journaled in the frame k, engages with the cog-wheel I', and to the shaft of this pinion is keyed the escapement ratchet-wheel L, the movement of which is controlled by a suitable double escapement-pawl carried by the upper end of the weighted pendulum-rod L'. 85

A cord, M, having one end secured to the cord-pulley H, passes through the top of the casing over the pulley N, and sustains the 90 weight O, that serves to impart the movement to the display-drum necessary to bring the cards before the opening of the casing.

Upon the end of the shaft C farthest from the escapement mechanism is placed the ratchet-wheel P, that is connected to the plate D', this ratchet-wheel and drum being loosely journaled on the shaft C, and a pawl, P', pivotally connected by the screw p to the side of the casing, engages with this ratchet and serves 95 to prevent any backward movement of the drum. The cards F are made of such size that 100

as the drum revolves each card will successively strike the top of the front opening, and will be detained thereby, thus showing the picture until the drum has traveled a sufficient distance to permit it to drop and display the advertisement upon the reverse side.

From the foregoing description the operation will be seen to be as follows: A crank-key is applied to the squared end of the main shaft, and by turning this key the weight-cord is wound upon the cord-pulley H. During this operation the ratchet-wheel P and pawl P' prevent the backward movement of the drum. The force of the weight, when wound up, tends to turn the cord-pulley, which communicates motion to the drum by the ratchet-wheel G and the pawl g. The ratchet-wheel H', engaging with the pawl I, turns the cog-wheel I'; but the movement of the cog-wheel, and consequently of the cord-pulley and drum, is controlled by the double pawl of the pendulum and by the escapement ratchet-wheel and pinion. It will thus be seen that the display-drum is caused to slowly revolve to bring the cards before the front opening of the casing.

I am aware that it has been heretofore proposed to construct an automatic advertising device with a rotating skeleton cylinder having rods with hooks to sustain the cards; and I do not wish to be understood as laying claim to any such construction.

Having thus described my invention, what I claim as new, and desire to secure by Letters Patent, is—

1. In an advertising device, the combination, with the inclosing-case having a sight-opening, and with the display-drum having the perforated end plates projecting beyond its periphery, of rods passing through said end plates and removably held therein, substantially as described.
2. In an advertising device, the combination, with the display-drum, of the perforated end plates, the rods removably held in said end plates, and the cards having each a pocket to receive a rod, substantially as described.
3. In an advertising device, the combination, with the drum having the perforated end plates projecting beyond its periphery, of the removable rods having bent ends and staples for holding said ends, substantially as described.
4. In an advertising device, the combination of the drum B, the shaft C, the ratchet-wheel P, the pawl P', the ratchet-wheel G and pawl g, the cord-pulley H, the cord M, the weight O, and the escapement mechanism, substantially as described.

JOHN McGREER.
